[57] CLAIM

The ornamental design for a pinball game housing for pre-school age children, substantially as shown and described.

DESCRIPTION

FIG. 1 is an oblique view showing the upper end, one side and the top of the pinball game housing for pre-school children;

FIG. 2 is a top plan view of the pinball game shown in FIG. 1;

FIG. 3 is an end elevational view of the end not visible in FIG. 1;

FIG. 4 is a side elevational view of the side not visible in FIG. 1; and

FIG. 5 is a bottom plan view.
